UNITED STATES PATENT OFFICE.

CONRAD HARRIS AND EDWARD KUMMER, OF CINCINNATI, OHIO, ASSIGNORS
TO C. HARRIS & SON, OF SAME PLACE.

DESIGN FOR A STOVE.

Specification forming part of Design No 6,321, dated January 28, 1873.

To all whom it may concern:

Be it known that we, CONRAD HARRIS and EDWARD KUMMER, of Cincinnati, county of Hamilton, State of Ohio, have invented a new and useful Design for a Coal and Wood Cooking-Stove to be known and called the "Moltke;" and we do hereby declare that the following is a full and exact description thereof, reference being had to the accompanying photographs and to letters of reference marked thereon, letter A showing a perspective view of the stove.

What we claim as our invention, and desire to secure by Letters Patent, is—

The moldings, scrolls, and configurations, as shown in accompanying photographs, so arranged and combined as to form an ornamental design for a coal and wood cooking-stove.

CONRAD HARRIS.
EDWARD KUMMER.
